WELL TOOL CONSTRUCTION

Jesse C. Wright, Los Angeles, and John H. Howard, Huntington Park, Calif.

Application November 26, 1934, Serial No. 754,762

5 Claims. (Cl. 255—61)

This invention relates to well drilling tools and relates more particularly to an improved construction for tools and equipment employed in the drilling of deep wells such as oil wells and gas wells. A general object of the invention is to provide a simple, practical sectional well tool whose parts or sections are dependably locked against detachment and separation.

Another object of the invention is to provide a well tool construction involving dependable means for locking the shank sections and cutters against separation and disconnection.

Another object of the invention is to provide a well tool in which the parts or sections may be tightly threaded together to their proper positions and then positively locked against unthreading.

Another object of the invention is to provide a well tool construction embodying means for positively locking the threadedly connected parts against separation that may be easily and quickly detached or removed to allow the parts to be disconnected for repair, replacement, etc.

Another object of the invention is to provide a well tool construction of the character mentioned in which a lock part is adapted to be arranged to engage a cutting part or blade of a cutting element to lock the cutting element against unthreading from the shank.

A further object of the invention is to provide an improved well tool construction of the character mentioned that is simple and inexpensive of manufacture.

The various objects and features of our invention will be fully understood from the following detailed description of a typical preferred form and application of the invention, throughout which description reference is made to the accompanying drawing, in which:

Fig. 1 is a side elevation of a well tool embodying the present invention with one quarter in longitudinal cross section. Fig. 2 is a transverse detailed sectional view taken as indicated by line 2—2 on Fig. 1. Fig. 3 is a transverse detailed sectional view taken as indicated by line 3—3 on Fig. 1. Fig. 4 is a fragmentary side elevation of the connected end portions of the shank sections illustrating the locking part in front elevation and Fig. 5 is a side elevation of one of the locking parts or keys.

The improved construction provided by this invention is adapted to be embodied in well tools and equipment varying considerably in character. Throughout the following detailed disclosure we will describe the invention embodied in

a typical preferred form of drilling tool for use in the rotary method of well drilling, it being understood that the invention is not to be construed as restricted to the specific form or application about to be described.

The well drilling tool illustrated in the drawing and embodying the invention includes, generally, a sectional shank 10, means 11 for locking the sections of the shank 10 against disconnection, a cutter 12 on the lower end of the shank 10, means 13 for locking the cutter 12 against detachment from the shank, a reaming or bore enlarging cutter 14 on the shank 10 and means 15 for locking the cutter 14 against detachment from the shank.

The shank 10 is an elongate sectional structure for carrying the cutters 12 and 14. The shank 10 may be of any desired length and may comprise any required number of parts or sections. In the particular tool illustrated in the drawing the shank 10 includes an upper section 16 and a lower section 17. Suitable means is provided on the section 16 for connecting it with a drilling string of drill pipe or the like. In the drawing we have shown a tapered screw-threaded pin 18 on the upper end of the section 16 adapted to be threaded into the socket of a part on the drilling string. The upper shank section 16 carries the bore enlarging cutter 14 and has a tapered threaded portion 19 on which the cutter 14 is arranged. An annular flange 20 is provided on the section 16 at the upper end of the portion 19 and its lower side forms a downwardly facing abutment shoulder 21 engageable by the upper end of the cutter 14. A longitudinal passage 9 is provided in the shank 10 to pass or handle the circulation fluid.

In accordance with the invention the shank sections 16 and 17 are connected by screw threads. In the preferred construction a reduced tapered screw-threaded pin 22 is provided on the lower end of the section 16 and is threaded into a socket 23 in the upper end of the section 17. The upper end of the section 16 may engage or bear upwardly against a shoulder 24 at the upper end of the pin 22. The adjacent end portions of the shank sections 16 and 17 are preferably of the same diameter as illustrated in the drawing. The lower end of the section 17 is formed to carry the bit or cutter 12. The cutter 12 is threadedly connected with the shank section 17 and the lower end of the section is provided with a tapered threaded pin 25. The pin 25 is reduced in diameter providing a downwardly facing shoulder 26 at its upper end.

The means 11 for locking the shank sections 16 and 17 against disconnection is such that the sections may be tightly threaded together in the usual manner and then positively locked against unthreading. In the simple form of the invention disclosed in the drawing the means 11 includes a plurality of circumferentially spaced projections or lugs 27 on the upper end portion of the section 17. In practice there may be four 10 equally spaced lugs 27. The lugs are elongated longitudinally of the shank and have vertical sides which may be substantially radial relative to the central longitudinal axis of the tool. The lugs 27 are preferably proportioned so that they 15 do not contact the wall of the well bore during the operation of the drilling tool.

The means 11 includes slots or grooves 28 in the section 16 above its pin 22. The grooves 28 extend longitudinally of the shank section 16 20 and are preferably identical in shape. The upper portions 29 of the grooves 28 may have flat parallel side walls and the intermediate portions 30 of the grooves have grooved side walls provided with overhanging dove-tailed flanges 31. The 25 grooves 28 have lower portions 32 which extend downwardly to the shoulder 24. The portions 32 are preferably shallower than the intermediate portions 30 providing upwardly facing shoulders 33 on the bottom walls of the grooves. The 30 portions 32 may have flat parallel side walls flush with and forming continuations of the inner sides of the flanges 31. The number and the circumferential spacing of the grooves 28 depend upon the 35 number of lugs 27 provided on the sections 17. Where there are four equally spaced lugs 27 there may be two grooves 28 spaced at approximately 120 degrees from one another. This relating of the grooves 28 with the lugs 27 insures the occurrence of a groove 28 adjacent the 40 forward side of a lug 27 regardless of the relative rotative positions assumed by the sections 16 and 17 when they are threaded together.

The lock means 11 includes a lock part or key 45 for arrangement in a groove 28. The key 34 is shaped to fit the groove and is adapted to project downwardly beyond the shoulder 24 to have cooperation with a lug 27. The lock part 34 is substantially rectangular in horizontal cross section and has an upper portion 35 shaped and proportioned to fit the intermediate portion 30 of the groove 28. Longitudinal dove-tailed tongues 36 are provided on the opposite side surfaces of the portion 35 to fit under and cooperate with the dove-tailed flanges 31. The inner side of the lock part 34 is stepped or provided with a downwardly facing shoulder 37 and a downwardly facing shoulder 38. The shoulder 37 is adapted to cooperate with the shoulder 33 while the shoulder 38 may cooperate with the upper 50 end of the shank section 17. The portion of the lock part 34 extending through the intermediate groove portion 32 may have plain flat side surfaces for cooperating with the walls of the groove to support the part 34 against lateral thrusts. 55 The lock part 34 has a tang or tongue 39 projecting downwardly beyond the shoulder 38 to cooperate with a lug 27. The inner surface of the tongue 39 may bear inwardly against the peripheral surface of the section 17. The tongue 70 75 39 is sufficiently long to have extensive cooperation with a side surface of a lug 27. Means is provided for preventing upward displacement of the lock part 34 from the groove 28. Threaded sockets 40 are provided in the inner or bottom walls of the groove portions 39. After the ar-

angement of the lock part 39 in a groove 28 a set screw 41 may be threaded in the socket 40 of the groove at the upper end of the lock part. The set screw 41 positively prevents upward shifting of the lock part in the groove 28. The upper outer corner of the lock part 34 may be bevelled off as illustrated in the drawing.

When the sections 16 and 17 of the shank are assembled they may be tightly threaded together so that the upper end of the section 17 abuts the shoulder 24. The lock part 34 is then slipped in a groove 28 which lies in a vertical plane adjacent the forward side of a lug 27 relative to the direction of rotation of the tool. The lock part 34 is fitted downwardly in the groove 15 until the tongues 36 have tight proper cooperation with the flanges 31 and the shoulder 37 bears against the shoulder 33. The shoulder 33 may cooperate with the upper end of the section 17. The tongue 39 then projects downwardly 20 to be engageable by the adjacent lock 27 to positively prevent unthreading of the sections 16 and 17. The set screw 41 may be threaded in the socket 40 to prevent displacement of the lock part 34. 25

The bit head or cutter 12 is provided on the lower end of the shank 10 to cut a pilot bore in the earth formation or to operate in a previously formed bore to center the tool. The cutter 12 includes a body or shoe 42 provided with a threaded socket 43 for receiving the pin 25. The shoe 42 may be threaded on the pin until its upper end bears upwardly against the shoulder 26. The cutter 12 includes cutting parts or blades 44 on the shoe 42. In practice the cutter 12 may have any desired number of spaced blades 44. In the particular case illustrated in the drawing there are three equally spaced cutting blades 44. The blades 44 project downwardly and outwardly from the shoe 42 and have lower cutting 49 edges 45 and side or reaming cutting edges 46. The lower cutting edges 45 may be inclined upwardly and inwardly and may be notched. The reaming edges 46 may be straight and substantially vertical. The upper outer corners of the 45 blades 44 are preferably bevelled or cut away as illustrated in Fig. 1 of the drawing. Spaced ports 47 are provided in the lower wall of the shoe 42 to discharge the circulation fluid downwardly between the cutting blades 47. 50

The means 13 for locking the cutter 12 against detachment from the shank 10 is similar to the means 11 described above. The means 13 includes one or more grooves 28a in the lower portion of the section 17 above the pin 25. Where there are 55 three circumferentially spaced blades 44 on the cutter 12 there may be two diametrically opposite grooves 28a. The grooves 28a may be identical in configuration to the grooves 28. A key or lock part 34a is adapted to be arranged in a 60 groove 28a to cooperate with or be engageable by a cutting blade 44. The key 34a may be of the same shape as the key 34. Longitudinal dove-tailed tongues 31a are provided on the lock part 34a to cooperate with dove-tailed flanges 31a on 65 the side walls of a groove 28a. A downwardly facing shoulder 37a is provided on the inner side of the lock part to cooperate with an upwardly facing shoulder 33a on the inner wall of a groove. A second downwardly facing shoulder 38a may 70 be provided on the inner side of the lock part 34a to cooperate with the upper end of the shoe 42. The lock part 34a has a lower end portion in the form of a tongue 39a which projects downwardly beyond the shoulder 38a for cooperating 75

with a cutting part or blade 44. A threaded socket 40^a is provided in the bottom wall of each groove 28^a to receive a set screw 41^a for locking the part 34^a against upward movement.

5 After the shoe 42 has been tightly threaded on the pin 25 so that its upper end bears against the shoulder 26 the lock part 34^a may be arranged in a groove 28^a to have its tongue 39^a adjacent the forward side of a blade 44. The two diametrically opposite grooves 28^a are related to the three equally spaced blades 44 so that a groove occurs adjacent the forward side of a blade when the shoe is threaded on the pin 25. The lock part 34^a may be passed downwardly in the groove 28^a 10 until its tongues 36^a cooperate with the flanges 31^a to tightly lock the part against movement. The shoulder 33^a and the upper end of the shoe 42 positively limit the downward movement of the lock part while a set screw 41^a may be threaded 15 in a socket 40^a to prevent upward movement of the lock part. The projecting tongue 39^a in front of a blade 44 dependably prevents unthreading of the cutter 12 from the shank.

The cutter 14 is provided to ream and enlarge 25 the well bore. The cutter 14 includes a tubular body 50 threaded on the portion 19 of the shank section 16. The cutter body 50 is preferably threaded on the portion 19 to a position where its upper end tightly bears against the shoulder 21. A plurality of spaced cutting blades 51 is provided on the cutter body 50. The blades 51 project outwardly or radially from the cutter body 50 and have lower cutting edges 52 and outer cutting edges 53. The lower cutting edges 30 35 52 engage or operate on the shoulder of the earth formation occurring between the rathole or pilot bore and the larger upper portion of the bore. The edges 52 may be straight and substantially horizontal. The outer cutting edges 53 are adapted to engage the side wall of the well bore and may be straight and substantially vertical. The upper outer corners of the cutting blades 51 are bevelled or cut away.

The means 15 for locking the cutter 14 against unthreading from the shank 10 is similar to the means 11 and 13. The lock means 15 includes a plurality of spaced grooves 28^b in the section 16 above the threaded portion 19. The grooves 28^b have intermediate portions provided at their side 45 50 walls with dove-tailed flanges 31^b. Upwardly facing shoulders 33^b are provided on the bottom walls of the grooves 28^b at the lower ends of the flanges 31^b. The grooves 28^b include lower portions 32^b extending downwardly through the flange 20 to the shoulder 21. The number and spacing of the grooves 28^b depend upon the number and spacing of the blades 51 of the cutter 14. The grooves 28^b are spaced and related so that one of them occurs in a plane adjacent a blade 51 regardless of the rotative position assumed by the cutter body 50 when properly threaded on the section 16.

The lock means 15 includes a lock part 34^b similar to the lock parts 34 and 34^a. The lock part 34 is shaped and proportioned to fit one of the grooves 28^b. The upper side portions of the lock part 34^b are provided with dove-tailed tongues 36^b for cooperating with the flanges 31^b. A downwardly facing shoulder 37^b is provided on 55 60 65 70 the inner side of the lock part 34^b to cooperate with the shoulder 33^b of one of the grooves. A reduced tongue 39^b projects from the lower end of the lock part and provides a downwardly facing shoulder 38^b on the inner side of the lock part 75 for engaging the upper end of the cutter body 50.

When the cutter body 50 has been tightly threaded on the shank portion 19 to a position where its upper end engages the shoulder 21 the lock part 34^b may be inserted in a groove 28^b that occurs adjacent a cutting blade 51. The cooperation of the shoulder 33^b with the shoulder 37^b and the cooperation of the shoulder 38^b with the upper end of the cutter body 50 limits the downward movement of the lock part. The tongues 36^b cooperate with the flanges 31^b to prevent the outward displacement of the lock part from the groove. A set screw 41^b may be threaded in a socket 40^b in the bottom of the groove to prevent upward movement of the lock part 34^b. When the lock part 34^b is properly set in position its tongue 39^b is engageable by a cutting blade 51 to prevent unthreading of the cutter body 50 from the shank section 16.

It is believed that the utility and practicability of the well tool construction will be readily apparent from the foregoing detailed description. It is to be noted that the shank sections and the cutters may be threaded together in the usual manner and then positively locked against detachment or disconnection by the lock means 20 25 of the invention. The lock means may be employed to lock the parts against unthreading without special manipulation of the parts or sections of the tool. The lock parts 34, 34^a and 34^b are effectively supported in their grooves against lateral strains or twists through the engagement of their side surfaces with the side walls of the grooves. The dove-tailed tongues of the lock parts cooperate with the dove-tailed flanges on the walls of the grooves to prevent outward displacement of the lock parts. The lock parts are held against longitudinal movement by the co-operation between the shoulders on their inner sides and the shoulders of the grooves and by the set screws in the upper portions of the 30 35 40 45 50 grooves. The provision of the lock means does not necessitate expensive modification of the tool or redesigning of the cutting elements. The construction of the present invention is adapted for embodiment in various types of well drilling tools and equipment and is not limited in its application to the specific class of tools illustrated in the drawing.

Having described only a typical preferred form and application of our invention, we do not wish to be limited or restricted to the specific form and application herein set forth, but wish to reserve to ourselves any modifications or variations that may appear to those skilled in the art or fall within the scope of the following claims:

Having described our invention, we claim:

1. A well tool including two sections threaded together, at least three circumferentially spaced projections on one section, the other section having at least two circumferentially spaced grooves, and means for locking the sections against unthreading including a removable lock part adapted to be arranged in one of the grooves to project therefrom for cooperation with a projection, the projections and grooves being related so that a groove is located adjacent the plane of a projection to receive the lock part to cooperate with the projection when the sections are properly threaded together.

2. A well tool including two threadedly connected sections, at least three circumferentially spaced cutting parts on one section, there being at least two circumferentially spaced grooves in the other section, and means for preventing disconnection of the sections including a lock part

adapted to be arranged in one of the grooves to project therefrom for cooperation with an adjacent cutting part.

3. A well tool including two threadedly connected sections, at least three circumferentially spaced cutting parts on one section, there being at least two circumferentially spaced grooves in the other section, and means for preventing disconnection of the sections including a lock part
- 10 adapted to be arranged in one of the grooves to project therefrom for cooperation with a cutting part, and means for retaining the lock part in the groove, the cutting parts and grooves being related so that one of the grooves is adjacent the plane of one of the projections to receive the lock part for cooperating with said projection when the sections are tightly threaded together.
- 15 4. A well tool including two threadedly connected sections, at least three circumferentially spaced projections on one section, there being at least two circumferentially spaced grooves in the other section, flanges on the walls of the grooves, and means for preventing unthreading of the sections including a key insertable in one of the

grooves to project therefrom and have cooperation with an adjacent projection, tongues on the key to cooperate with the flanges to prevent outward movement of the key, and means holding the key against longitudinal movement in both 5 directions.

5. A well tool including a shank, a tubular cutter body threaded on the shank, at least three circumferentially spaced blades on the cutter body, there being circumferentially spaced 10 grooves in the shank, and means for locking the cutter body against unthreading from the shank including an elongate key insertable downwardly in a groove and adapted to project therefrom to cooperate with a blade, the number and circumferential disposition of the blades and grooves being such that a groove is positioned adjacent the plane of a blade to receive the key when the cutter body is threaded to position on the shank, 15 and means for preventing upward movement of the key in the groove.
